UNITED STATES PATENT OFFICE.

EDGAR H. FREEMAN, OF TRENTON, NEW JERSEY.

SEPARABLE-HUSK-SOCKET FITTING.

1,145,361.

Specification of Letters Patent.

Patented July 6, 1915.

Application filed March 27, 1914. Serial No. 827,710.

To all whom it may concern:

Be it known that I, EDGAR H. FREEMAN, a citizen of the United States, residing at Trenton, in the county of Mercer and State 5 of New Jersey, have invented certain new and useful Improvements in Separable-Husk-Socket Fittings, of which the following is a specification.

This invention relates to the general subject of electrical lamp sockets, and has special reference to a novel separable lamp socket construction possessing special utility in its application to the modern "husks" or socket coverings which are now extensively 15 employed in electric lighting fixtures.

To this end, the invention contemplates a lamp socket construction wherein the various members thereof are so related that they may be easily assembled and taken apart, thereby greatly facilitating the wiring of the socket to the fixture as well as the convenient manipulation thereof for purposes of repair or replacement of parts. In this connection, the invention proposes to provide a construction of socket which may be termed a quick detachable lamp socket for husk fittings; that is to say, a socket wherein the receptacle or lamp carrying member thereof may be easily and quickly removed 20 from within the husk, and quite as readily and easily replaced at will, without disturbing the husk or its support or without disturbing the wiring connections with the wire terminals of the socket. This is a very 25 desirable feature in husk fittings by reason of obviating the many objections to the ordinary methods of mounting lamp sockets within husks, particularly with reference to the difficulty of fastening the socket and 30 husk together onto the supporting fixture, and the general inaccessibility, of the ordinary sockets within a husk, for wiring purposes.

A further object of the invention is to 45 provide a lamp socket construction for husk fittings including novel interior fastening means for tightly and rigidly securing the husk and the socket to the supporting fixture, the interior fastening including means 50 for positively locking both the husk and the socket against turning, thereby overcoming one of the objections to husk socket fittings which frequently loosen and turn with the screwing in and out of the lamp.

55 With these and other objects in view

which will be readily apparent to those familiar with this class of devices, the invention consists in the novel construction, combination, and arrangement of parts hereinafter more fully described, illustrated, 60 and claimed.

Though susceptible of structural change in nonessential particulars, a preferred and practical embodiment of the invention is shown in the accompanying drawings, in 65 which—

Figure 1 is a complete sectional view of the complete husk fitting including the separable socket mounted therein and wired. Fig. 2 is a vertical sectional view illustrating the interior fastening means for locking the cap member of the socket casing and the husk to the nipple of a fixture bracket. Fig. 3 is a cross sectional view on line 3—3 of Fig. 2. Fig. 4 is an external perspective 70 view of the casing cap member of a separable socket. Fig. 5 is a view similar to Fig. 2 but illustrating the application of the special tool that is preferably employed for screwing home the interior locking nut 75 that secures the cap member and husk very rigidly to the supporting fixture. Fig. 6 is a sectional elevation showing the various parts of the separable socket in their separated relation and illustrating the manner 80 of inserting and connecting such parts within the husk. Fig. 7 is a cross sectional view on the line 7—7 of Fig. 6 illustrating in plan the arrangement of the wire terminal plates on the wire terminal base-piece which 85 is held by the wires within the bottom part of the rigidly-secured cap member of the socket casing. Fig. 8 is a detail in perspective of the said wire terminal base-piece. Fig. 9 is a sectional view of the receptacle or 90 switch member of the socket, the line of section thereof being indicated by the line 9—9 on Fig. 1 of the drawings.

Like reference characters designate corresponding parts in the several figures of the 100 drawings.

In adapting the improved quick detachable or separable lamp socket to a husk fitting, no alteration is required in the husk itself nor in the supporting fixture or 105 bracket, so for illustrative purposes there is shown in the drawings a section of a hollow lamp fixture bracket, designated by the numeral 1, and having associated therewith the ordinary hollow wiring nipple or button 110

2 which is provided with the usual threaded section 3 and an annular abutment shoulder 4. The threaded section 3 of the nipple 2 is adapted to receive and project through the top opening in the crown of the usual husk or socket covering 5, thus permitting the crown of the husk to be held against the abutment shoulder 4. To provide for rigidly securing and locking the husk in this position, the present invention provides an interior fastening means associated with and carried by the metallic cap member 6 of the socket casing, which comprises the said cap member and a metallic shell member 7 separably connected at their adjoining ends by a screw connection 8 provided by corresponding threads on the said two members of the socket casing. The interior fastening means consist of the said cap member 6 and an interior rotatable locking nut 9 which is loosely swiveled within a chambered holding collar 10 projected from the crown of the cap member 6 and preferably formed integral therewith. The loose swiveled mounting of the locking nut 9 may be conveniently provided for by forming such nut with an annular groove 11 and providing the wall of the collar 10 with prick-punches 11^a forming interior retaining projections that loosely engage in said groove 11 and serve to retain the nut within the crown of the cap member 6 at all times. In addition to the locking nut 9 which is adapted to be screwed onto the threaded section 3 of the wiring nipple 2, the outer side of the holding collar 10 is formed with a plurality of pointed fastening spurs 12 which are adapted to be forcibly crowded by the nut 9 into fastening or locking engagement with the metal of the husk 5 at the crown thereof. Inasmuch as it is preferable to form the metallic cap members 6 of steel, or of a harder grade of metal than that of the husk 5, it will be apparent when the nut 9 is tightly screwed home, the spurs 12 will be caused to pierce the metal of the husk and crowd against the abutment shoulder 4 of the wiring nipple, with the result of very effectually locking the socket cap member 6 and the husk 5 to the wiring nipple and positively preventing the turning or loosening thereof under any of the ordinary strains to which the electrical lamp socket is subjected.

In order to manipulate the locking means, either for securing the husk and socket onto the supporting wiring nipple 2, or for detaching the same therefrom, it is preferable to employ a special implement or tool for this purpose, and a practical form of tool that may be thus utilized is shown in Fig. 5 of the drawings in its applied position.

Referring to the preferable construction of the applying-tool, it will be observed by reference to Fig. 5 of the drawings that the same includes in its organization a main

supporting bushing 13 which snugly registers within the socket cap member 6, substantially filling the entire internal space of the same, and provided at one side with holding projections 14 adapted to loosely interlock within the switch key slot 15 formed in the wall of the cap member 6, so as to securely lock the bushing against rotative movement when the same is inserted within the cap member 6. In addition to the holding projections 14 projecting from the periphery thereof, the said main supporting bushing 13 of the tool is adapted to have removably inserted into a keeper socket 16 therein, the tenon 17 of an alining pin 18. 75 This alining pin is adapted to be inserted through the key slot 19 of the husk and also through the key slot 15 of the cap member 6 and into the said keeper socket 16, thus providing means, in combination with the holding projections 14, for alining the cap member and the husk so that the key shaft of the socket proper will project through both, without loosening the cap member or the husk. In addition to the elements referred to, the said applying-tool includes a rotatable wrench spindle 20 journaled in the longitudinal bearing opening 21 extending through the bushing 13, and provided at one end with a spanner wrench head 22 having 90 the opposite chuck projections 23 adapted to engage in the tool grooves 24 formed in one face of the locking nut 9. The opposite end of the wrench spindle 20 carries a suitable operating handle 25 to be manipulated by 100 the workman. It will thus be seen that with the applying-tool arranged in the position shown in Fig. 5 of the drawings, the husk and the socket cap member 6 are properly alined and firmly held in position over the 105 threaded section of the wiring nipple 2, while the operator turns the wrench spindle 20 and tightly screws home the locking nut 9 in order to effect the locking together of the parts in the manner already pointed out. 110 When this is accomplished, the alining pin 18 is drawn out from the keeper socket 16 so that the tool or wrench can be readily pulled out of the fixedly positioned socket cap member 6. 115

From the foregoing description, it will be observed that the husk and the socket cap member 6 in their applied position remain fixed and stationary upon the wiring nipple or other supporting fixture, thus 120 making it possible for the wireman to very easily wire up the socket and assemble the socket parts, and quite as easily separate or detach the socket parts and the wires whenever necessary for any purpose. 125

As already indicated, the main casing for the interior socket parts comprises the cap member 6 and the shell member 7 detachably united by the screw connection 8, and in addition to this separable or two-part 130

casing, the improved socket includes a wire terminal base-piece 26 and a receptacle member 27 which are also separably related in the manner to be now explained. First, 5 with reference to the wire terminal base-piece 26, the same preferably consists of a one-piece circular block of insulating material formed with a center wire opening 27^a therein and chambered at its inner side, as 10 indicated at 28 to form seats which receive therein the oppositely arranged wire terminal plates 29—29 of duplicate construction. Each of these plates is held to its seat within the chamber or recess 28 by means of a 15 suitable retaining screw 30 passing through the body of the base-piece and engaging a threaded opening in the plate. Each of the terminal plates 29 is provided with a binding screw 31 for securing a wire terminal 20 thereto, and at one side of its retaining screw 30, each of said plates has an angled formation and is longitudinally split, as at 32, to provide a spring forked contact 33 having a receiving opening 34 for separable 25 connection therewith of the circuit terminal elements of the receptacle member 27 of the socket, as will be presently explained. The said wire terminal base or block 26, having the said wire terminal plates which are arranged and constructed as described, is of substantially the same external diameter as the internal diameter of the socket cap member 6 and is shaped to conform to the interior of the latter at the crown thereof, so 30 that the said wire terminal base will snugly register inside of the crown of the cap member 6, as clearly illustrated in Figs. 1 and 6 of the drawings. This wire terminal base affords very simple and convenient means 35 for giving ready accessibility to the socket for wiring purposes, as it will be observed by reference to the drawings that in wiring the improved socket it is only necessary for the workman to draw the line wires 40 through the fixture 1—2 and through the socket cap member 6, so that with the wire terminal base entirely removed from the cap member, the wire ends can be passed through the center wire opening 27^a of the 45 base and conveniently secured to the binding screws 31 of the respective wire terminal plates 29. After thus attaching the line wires to the wire terminal plates of the base 26, the line wires are drawn back 50 through the fixture and at the same time the wire terminal base 26 is moved into its position within the crown portion of the cap member 6, where it will then be held stationary by the line wires themselves, as will be 55 readily apparent from the illustration of Fig. 6 of the drawings. In placing the wire terminal base 26 within the socket cap member 6, the same is guided to and held in a fixed position against rotative displacement 60 by suitable guiding and retaining means,

preferably consisting of a longitudinally disposed inwardly projecting guide rib 34 formed on, or carried by, the socket cap member 6 and a retaining groove 35 formed in the external periphery of the wire terminal base 26 and slidably interlocking with the said rib 34, as best seen in Figs. 6 and 7 of the drawings. It is by reason of the interlocking engagement of the rib 34 and the groove 35 that the wire terminal base 26 is held in a fixed operative position to separably receive the circuit terminal elements 36 and 37 respectively of the detachable receptacle member 27 of the socket. 70

The detachable receptacle member 27 of the socket may be of the key or keyless type, but for purposes of illustrating the invention the same is shown in the drawings as being of the key type of receptacle member having a switch mechanism for opening and closing the electrical circuit through the lamp. This receptacle member includes a body 38 of porcelain or other suitable insulating material which is adapted to slidably register within the cap member 6 of the socket, and is provided in its peripheral wall, with a retaining groove 38^a which is also adapted to engage the guide rib 34 of the cap member 6 to insure the proper alignment of the receptacle member with the wire terminal base and also to prevent rotative movement of the receptacle member when the lamp is screwed in and out of position. The insulating body 38 of the receptacle member has fitted to one side thereof, the usual screw shell contact 39 to which is metallically connected one end of a combined fastening and conducting screw 40 which passes entirely through the insulating body 38, and at the side thereof opposite the screw shell contact 39 has a projecting contact pin which constitutes the circuit terminal element 37 which detachably engages with the spring contact 33 of one of the wire terminal plates 29. The other of said circuit terminal elements designated by the numeral 36 is also in the form of a contact pin which detachably engages the spring contact 33 of the other wire terminal plate 29, and is formed by the projecting end of a fastening and conducting screw 41 fitted in the insulating body 38 and engaging with a switch contact plate 42 seated in the chambered side of the body 38 opposite the screw shell contact 39 and having its free end arranged for engagement by the rotatable switch block 43 of the switch mechanism carried by the said body 38. This switch mechanism includes, in addition to the plate 42 and the switch block 43, the snapping spring 44 for the switch block which is permanently in engagement therewith and is seated within the bottom of a switch chamber 45 formed within the insulating body 38. This snapping spring has 130

a screw or equivalent metallic connection 44^a with the center plug contact spring 45 seated on one side of the body 38 centrally within the bottom portion of the screw shell 5 contact 39, said screw shell contact receiving the plug of the lamp in the usual manner and being insulated from the shell member 7 of the socket casing by suitably interposed insulating material 46.

10 The rotatable switch block 43 is of the type which has a limited play on a key shaft 47 journaled in suitable bearings and having an exteriorly arranged operating key 48 adapted to be disposed outside of the 15 husk or socket covering 5. The said key shaft 47 is adapted to project from one side of the insulating body 38 outward through the respective key slots 15 and 19 of the cap member 6 and of the husk 5, as plainly shown 20 in Figs. 1 and 6 of the drawings.

After the wire terminal base 26 has been positioned within the crown portion of the fixed cap member 6, as before described and as it appears in Fig. 6, the receptacle 25 member 27 is brought into operative position simply by the act of inserting it upward within the cap member 6. This is accomplished by first tilting the receptacle member to an inclined position, as indicated 30 by the dotted lines in Fig. 6 of the drawings, so that the operating key may be passed outward through the key slot 19 of the husk. Then the receptacle member is straightened and moved upward into the 35 cap member 6 with the retaining groove 38^a of the receptacle member 38 engaged with the guide rib 34 of the cap member. Thus the receptacle member is correctly guided into play so that the contact pins, or circuit 40 terminal elements 36 and 37 thereof, are caused to move into contacting engagement with the spring forked contacts 33 of the respective wire terminal plates, thereby establishing the circuit connections through 45 the socket, subject to the opening and closing of the switch. After the receptacle member is thus positioned, the secure retention of the assembled parts is completed by screwing the shell member 7 onto the threaded end of the cap member 6, said shell member having a flared portion 49 which receives one end of the insulating body 38 of the receptacle member. To remove the receptacle member for replacing or repair, or 50 for the purpose of gaining access to the wire terminals, it is only necessary to unscrew the shell member 7 and manually withdraw the receptacle member 27, as may be readily appreciated from an inspection of Fig. 6 of the drawings.

In order to more effectually complete the insulation of the switch mechanism and only leave exposed the contact pins 36 and 37 for engagement with the terminal plates on the 55 wiring base, an insulating cover plate 50

made of insulating paper or other insulating material is placed over the pins 36 and 37 and entirely covers the switch chamber 45 and the elements of the switch mechanism.

From the foregoing, it is thought that the construction, operation, and many advantages of the herein-described separable husk socket fitting will be readily apparent without further description, and it will be understood that various changes in the minor details of construction may be resorted to without departing from the spirit or sacrificing any of the advantages of the invention.

I claim:

1. A separable husk fitting comprising in combination with the hollow wiring element, a husk engaging said element, and an electrical socket arranged inside of the husk and including a cap member internally fastened to the wiring element, a wire terminal base seated within the crown portion of the cap member, a receptacle member received within the cap member and detachably connecting with the wire terminal base, and a shell member having a separable connection with the cap member.

2. A quick detachable socket of the class described, comprising in combination with the hollow wiring element, a metal cap member having a locked connection at its crown with said element, a wire terminal base seated within the crown portion of the cap member and having wire terminal plates for the line wire terminals, said base being retained in place by the connection of the wires therewith, a detachable receptacle member received within the cap member and carrying circuit terminal elements having separable engagement with the wire terminal plates, and means for removably holding the receptacle member within the cap member.

3. A quick detachable socket of the class described, comprising in combination with the hollow wiring element, a cap member having a locked engagement at its crown with said wiring element, a wire terminal base removably seated within the crown portion of the cap member, and provided with wire terminal plates each having a spring contact, a receptacle member having circuit terminal connections detachably engaging said spring contacts of the wire terminal plates, said receptacle member also carrying the electrical plug contacts, and means for removably holding the receptacle member within the cap member.

4. A quick detachable socket of the class described, comprising in combination with the hollow wiring element, a cap member having a locked engagement at its crown with said wiring element, a wire terminal base removably seated within the crown por-

tion of the cap member and provided with wire terminal plates each having a spring contact, a receptacle member having circuit terminal connections detachably engaging said spring contacts with the wire terminal plates, said receptacle member also carrying the electrical plug contacts and having a slidable interlocking engagement with the cap member, and means for removably holding the receptacle member within the cap member.

5. A quick detachable socket of the class described, comprising in combination with the hollow wiring element, a cap member having a locked connection with said wiring element, a wire terminal base removably seated within the crown portion of the cap member and having a slidable interlocking engagement therewith, said base being held 0 in position by the line wires and provided with terminal plates therefor, each of said terminal plates having a forked contact, a receptacle member received within the cap member and having circuit terminal ele- 5 ments detachably engaging the forked contacts of the wire terminal plates, said receptacle member also carrying the electrical plug contacts and having a slidable interlocking engagement with the cap member,

and means for removably holding the receptacle. 30

6. A quick detachable socket of the class described, comprising in combination with the hollow wiring element, a cap member having a locked connection with said wiring 35 element, a wire terminal base removably seated within the crown portion of the cap member and carrying wire terminal plates for a supporting connection of the line wires therewith, a receptacle member removably received within the cap member and carrying the screw shell contact and center plug contact for the electrical plug, said receptacle member also having projecting circuit terminal contact pins separably engaging with the wire terminal plates, and a key switch mechanism included in the circuit between said contact pins and the plug contacts, and a shell member having a separable connection with the cap member for retaining 40 the receptacle member in position. 45

In testimony whereof I hereunto affix my signature in the presence of two witnesses.
